UNITED STATES PATENT OFFICE.

EUGENE C. AMSDEN, OF BOSTON, MASSACHUSETTS, ASSIGNOR TO CHARLES C. KENNEY, OF WESTON, MASSACHUSETTS.

DESK HINGE.

Application filed March 15, 1924. Serial No. 699,569.

To all whom it may concern:

Be it known that I, EUGENE C. AMSDEN, a citizen of the United States, residing at Boston, in the county of Suffolk and State 5 of Massachusetts, have invented certain new and useful Improvements in Desk Hinges, of which the following is a specification.

The invention to be hereinafter described relates to hinges for connecting the cover to the body of a desk, and for other similar uses.

One of the purposes of the invention is to provide a strong and simple hinge construction provided with a stop means for 15 limiting the extent of opening movement of the desk cover, the construction being such that the hinge cannot cause injury to articles contained within the desk.

With the aforesaid and other purposes in view, the character of the invention will be best understood by reference to the following description of one good form thereof, shown in the accompanying drawings, wherein:

Fig. 1 is a perspective view of a desk body and cover provided with hinges embodying the invention, the hinges being shown in dotted lines;

Fig. 2 is a sectional view of a portion of 30 the desk showing the relation of the members of the hinge when the cover is in open position;

Fig. 3 on an enlarged scale is a perspective view of one of the hinges; and

Fig. 4 is an edge view of one of the 35 hinges.

Referring to the drawings, 1 designates the body of a desk having a top board 3 and a cover 5 which is connected to the body of 40 the desk by a pair of hinges which are similar in construction, and therefore, a description of one will suffice for both.

The hinge shown herein as one good form of the invention, comprises a member 7 which may be stamped or pressed from sheet metal. This member has a body 9 of general segmental form and has an attaching flange 11 provided with screw holes 13 through which screws 15 may be entered to secure 45 the flange to the top board of the body. Projecting from one end of the body is a tongue 17 provided with screw holes 19 through which screws 21 may be entered to 50 secure the tongue to one of the sides of the desk body.

To contribute to the secure connection of the member 7 with the desk body, said member may be formed to provide a pair of prongs 23 and 25 projecting transversely to the plane of the member. The prong 23 60 may desirably be substantially at the junction of the tongue 17 with the body 9 of the member, and the prong 25 may desirably be at the end of the tongue.

It is desirable that the body 9 shall be 65 spaced a slight distance from the inner face of a side of the desk. To accomplish this, in the present instance, the member is provided with lugs 27 and 29 at points spaced on the perimeter of the curved edge of the 70 body, and the tongue 17 is offset somewhat from the plane of the body. Also, the prong 23 may project from a lug 31 which may assist in holding the member in spaced relation with respect to the inner face of the 75 side of the body.

Extending upward from the body adjacent the flange 11 is a projection 33 adapted to occupy a kerf cut in the top board 3.

The hinge also comprises a member 35 80 which may be stamped or pressed from sheet metal. This member has a flange 37 provided with holes 39 through which screws 41 may be entered for securing the member to the desk cover. Extending from the member adjacent the flange 37 is a projection 43, and the projections 33 and 43 have registering holes through which a rivet 45 may be entered.

To limit the opening movement of the 90 cover, the member 35 may have a portion 47, in the present instance, formed to provide a hook 49 adapted to engage the lug 31 as a stop when the cover is in open position, as will be noted in Fig. 2. The portion 47 of 95 the member 35 extends into the space between the body 9 and the inner face of the side of the desk, and the body 9 is so constructed and arranged that the outer end of the portion 47 does not project beyond the 100 curved perimeter of the body when the cover is rocked through open or closed position. As a consequence, the body 9 serves as a shield to protect the portion 47 of the member 35 from engagement with articles 105 in the desk, and there is no possibility of injuring the same.

In opening the cover of the desk, the hook 49 is liable to come into contact with the stop lug 31 with a sharp blow, but the 110

prongs 23 and 25 will effectively resist such a blow and prevent the screws 21 in the tongue 17 from becoming loosened. Since the portion 47 of the cover member of the hinge is confined between the body 9 and the inner face of the side of the desk, any tendency of lateral movements of the cover member 35 will be effectively resisted.

By my invention there is provided a strong, simple hinge construction which is cheap to manufacture, and is effective in operation.

It will be understood that the invention is not limited to the specific embodiment shown, and that various deviations may be made therefrom without departing from the spirit and scope of the appended claims.

What is claimed is:—

1. A desk hinge comprising a pair of pivotally connected members having provision for securing the same to the body and cover respectively of the desk, the body member having provision for spacing the same slightly from a side of the desk, a stop, and a pair of prongs adjacent the stop adapted to be driven into the side of the desk, and the cover member having a portion adapted to swing in the space between the body member and the side of the desk and come into engagement with the stop to limit opening movement of the cover.

2. A desk hinge comprising a plate of general segmental form having parts provided with screw holes for receiving screws for securing the plate to the body of the

desk, and elements projecting laterally from the plate for spacing the latter slightly from the side of the desk, a member having holes for receiving screws for securing the same to the cover of the desk, and a portion adapted to swing in the space between the segmental plate and the side of the desk and come into engagement with a part of the plate as a stop, and projections extending from the plate and member provided with means pivotally connecting the same.

3. A desk hinge comprising a plate of general segmental form provided with screw holes for receiving screws for securing the plate to the body of the desk, said plate being adapted for location to leave a slight space between the plate and the inner face of a side of the desk, and a member pivotally connected to said plate and having holes for receiving screws for securing the member to the cover of the desk, said member having a portion projecting down along the plate at the side of the plate adapted to face the inner face of the side of the desk, said portion being adapted to swing into engagement with a part of the plate as a stop to limit opening movement of the cover, said projecting portion of the member being wholly covered and protected by said plate as it swings on opening and closing movements of the cover, thereby to prevent said member from engaging or injuring articles in the desk.

EUGENE C. AMSDEN.
